METHOD FOR PRODUCING STREAMLINED MODELS

William H. Caraway, Sugar Land, Tex.

Application January 8, 1943, Serial No. 471,740

1 Claim. (Cl. 73—148)

(Granted under the act of March 3, 1883, as amended April 30, 1928; 370 O. G. 757)

The invention described herein may be manufactured and used by or for the Government for governmental purposes, without payment to me of any royalty thereon.

This invention relates to a method for developing streamlined forms offering the least resistance to fluid flow.

It is an object of this invention to provide a method whereby the optimal streamlined form may be determined in a minimum time and with a minimum effort.

This and other objects and advantages of my invention will become apparent upon a consideration of the following description and the accompanying drawing, in which:

Fig. 1 is a plan view of a model boat incorporating the features of the invention; and

Fig. 2 is a cross-section taken along the line 2—2 of Fig. 1.

I prefer to use as a base for the model a wooden form cut roughly to shape and provided with means whereby it may be supported in the medium in which it is designed to operate. The rough form thus provided is then covered with a material which is soluble or erodable in that particular medium. The form is then placed under conditions analogous to the conditions for which it is designed and the medium will wear away its surface in conformity with the pressure variations created by the flow. Since the erosive effect of the water is proportional to the resistance offered, the wearing away will be greatest at the areas of highest resistance and consequently the final form taken by the model will be that which affords the least resistance to the flow of the medium. This wearing away will automatically shape the model into the optimal streamlined form.

While my invention has particular applicability to the design of boats, it is clear that it is equally adaptable to other devices subjected to fluid stream flow such as aeroplane wings, fuselages, or the like. However, for the purposes of clarity and understanding of my invention, the following description will be limited to its application to boats.

Referring to the figures, the numeral 1 represents the hull of the roughed out model which is provided with strengthening ribs 3 and cross strengthening members 5 to which the securing device 7 may be attached. If it is desired to place the model in a basin and have it towed through the water, either the securing device 7 may be used or a line may be attached to the eye-bolt 9. Over the outside of the hull a relatively thick

coating 11 of a water soluble material is placed and allowed to harden. The coating used should be such that the wearing away through the erosion of the coating will not be too rapid. I have found the water soluble resins to be quite satisfactory for this purpose.

The model having been prepared as described above, it is weighted so that it will float at the proper depth or it can be held to the desired displacement by means of the securing device 7. It is then placed in the testing basin and the water passed by the model while it is held stationary or the model may be towed in the basin. After the model has been in the basin a sufficient length of time, it is removed and can be used as a mould for producing further test models or, if desired, the dimensions may be taken directly from it and suitably scaled for use in a full sized boat.

Under some circumstances it may be desirable to omit the roughed-out wooden form. In this case, a block of the solidified water soluble or erodable material may be roughed out and the center hollowed out forming a hull which will approximate the final form. The strengthening members 3 and 5 are placed in position and the test carried out as described above.

Where the object to be streamlined is intended for use in a gaseous medium, the coating or hull may be made of a relatively soft material such as talc or chalk and subjected to an air blast containing fine abrasive particles such as sand, emery, or the like.

While I have described my invention with particularity, it is to be understood that I do not wish to be limited to the particular details and arrangements disclosed since various modifications within the spirit of the invention will suggest themselves to one skilled in the art.

Having thus described my invention, what I claim as new and wish to secure by Letters Patent is:

A method for producing streamlined forms comprising the steps of shaping a base of rigid material to approximate form, coating the base with a water soluble resin, floating the coated base in a water medium, and effecting a flow of the water medium past said coated base under controlled conditions of displacement and relative velocities between said base and said medium, whereby areas of the coating offering high resistance are removed at a greater rate than areas offering low resistance.

WILLIAM H. CARAWAY.
